US00D828476S

(12) **United States Design Patent** (10) Patent No.: **US D828,476 S**
Smith et al. (45) Date of Patent: ** Sep. 11, 2018

(54) **FIREARM STOCK**(71) Applicant: **VISTA OUTDOOR OPERATIONS LLC**, Farmington, UT (US)(72) Inventors: **Paul N. Smith**, Bozeman, MT (US); **Robert A. Kincaid**, Manhattan, MT (US); **Daniel D. Sereday**, Belgrade, MT (US); **Troy E. Lance**, Livingston, MT (US); **Christopher J. Michael**, Belgrade, MT (US); **Oscar C. Woods**, Bozeman, MT (US)(73) Assignee: **Vista Outdoor Operations LLC**, Farmington, UT (US)(**) Term: **15 Years**(21) Appl. No.: **29/586,962**(22) Filed: **Dec. 8, 2016**(51) LOC (11) Cl. **22-01**

(57) **CLAIM**

We claim the ornamental design for the firearm stock, as shown and described.

DESCRIPTION

FIG. 1 is a top, front perspective view of a firearm stock according to an embodiment of the disclosure.

FIG. 2 is a rear, bottom perspective view of the firearm stock.

FIG. 3 is a left side view of the firearm stock.

FIG. 4 is a right side view of the firearm stock.

FIG. 5 is a top view of the firearm stock.

FIG. 6 is a front view of the firearm stock.

FIG. 7 is a rear view of the firearm stock; and,

FIG. 8 is a bottom view of the firearm stock.

The portions shown in dashed lines form no part of the claimed design.
